UNITED STATES PATENT OFFICE.

MONTGOMERY DENNIS, OF BELLEVILLE, NEW JERSEY, ASSIGNOR OF ONE-HALF TO THE GEORGE BROWN & COMPANY, OF NEW JERSEY.

CROSS-TOOLING AND CRANDALLING MACHINE.

SPECIFICATION forming part of Letters Patent No. 650,809, dated May 29, 1900.

Application filed July 24, 1899. Serial No. 724,906. (No model.)

To all whom it may concern:

Be it known that I, MONTGOMERY DENNIS, a citizen of the United States, residing at Belleville, in the county of Essex and State of New Jersey, have invented certain new and useful Improvements in Cross-Tooling and Crandalling Machines; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to certain improvements in that class of stone-working machines represented by the one shown in my prior patent, No. 595,094, dated December 7, 1897.

The objects of the invention are to give to the surface of the stone a peculiar finish somewhat resembling in effect to the eye the crandalling-marks heretofore performed by hand and to obtain other effects difficult, if not impossible, to imitate practically by the hand, and to secure other advantages and results, some of which may be referred to hereinafter in connection with the description of the working parts.

The invention consists in the improved stone-finishing or cross-tooling machine and in the arrangements and combinations of parts of the same, all substantially as will be hereinafter set forth, and finally embraced in the clauses of the claim.

Referring to the accompanying drawings, in which like letters of reference indicate corresponding parts in each of the several views, Figure 1 is a front elevation of the cross-tooling and crandalling machine embodying my improvements. Fig. 2 is a detail view, on an enlarged scale and partly in section, showing means for transmitting power and movement to the tool-carrier. Fig. 3 is a sectional view at line y', Fig. 4, of a ratchet-wheel and pawl; and Fig. 4 is a plan of the same. Fig. 5 is a section taken on line y, Fig. 2. Fig. 6 is a perspective view of a certain link adapted to receive a double eccentric and transmit the motion thereof to the tool-carrier. Fig. 7 is a detail side elevation of the tool-carrier and its connections.

Fig. 8 is a section of the same on line x. Fig. 9 is a detail plan showing the connection of a screw-shaft with the means for imparting short longitudinal reciprocating movements thereto, the sections being taken on line x', Fig. 10. Fig. 10 is a front view of the same, and Fig. 11 is a front view of a lever to which the reciprocating screw-shaft is connected. Fig. 12 is a section through line z in Fig. 1.

In said drawings, a indicates the frame or bed of an ordinary stone-planing machine having vertical bearings or ways a' on which certain tool-supporting devices may operate and having means a² for raising and lowering said tool-supporting devices.

b is a movable carriage or table adapted to support and carry the stone beneath the finishing-tool v, suitable means c c' c² c³ c⁴ of any ordinary construction being provided to operate the said table to secure the desired reciprocation of said table.

On the frame a or on the vertical slideways a', at opposite sides thereof, is arranged a horizontally-disposed and vertically-movable slideway f, and on the said slideway is arranged a horizontally-movable head f', operated by a hand-screw f². Upon said vertically-movable horizontal slideway f', at the opposite ends thereof, are formed boxes or bearings d d, which are movable vertically with the said horizontal slideway and carry the horizontal shaft d', so that it lies parallel with the vertically-movable horizontal slideway and movable with the same. The said vertically-movable horizontal slideway is adjusted or raised and lowered by means of the screws a² before referred to. These last operate simultaneously, and as they are uniformly threaded the said horizontal slideway f is adjusted vertically while maintaining its proper horizontal relation to the stone-carriage b. On the said head are formed vertical slideways f³ for a tool-carrier g, forming a part of said head, said carrier having a vertical reciprocating motion in said slideway, secured by means of a link h, arranged on cams or eccentrics e e', so as to be movable reciprocally thereby as the said cams rapidly rotate with the shaft d'. At its end opposite the eccentrics e e' the said link h is connected to said tool-carrier g, and thus the rapid reciprocating movement of the link is trans-

mitted to said carrier and thence to the tool *v*, as will be understood. The tool-carrier may be provided with means for changing the inclination of the tool and for fastening 5 said tool on said carrier. To operate said cam-shaft *d*, I provide bevel-gearing *k l*, a shaft *m*, another set of bevel-gearing *n o*, and means for transmitting motion, such as short shaft *o'*, bevel-gears *o² o³*, shaft *o⁴*, leading 10 from the front of the machine to the back thereof, and another set of bevel-gearing *o⁵ o⁶*, the last being on a clutch-sleeve *o⁷*, having suitable clutch-jaws *o⁸*, adapted to engage a co-operating clutch *o⁹*, fast upon the main driving-shaft *c'*.

The clutch members *o⁸ o⁹* are thrown from clutching relation when the machine is to be employed in planing the stone; but when the crandalling or cross-tooling is to be effected 20 the said members *o⁸ o⁹* are clutched. The said power-transmitting means are of a positive character, whereby there will be no material lost motion at any point between the said main driving-shaft and the tool-carrier. 25 In connection with said main driving-shaft *c'* and with the means above referred to for transmitting power or motion to the shaft *d'* and tool-carrier I have provided means for moving the table *b* longitudinally upon its 30 slideways or bearings *a⁴* of the bed or frame, said means for operating the table being of any kind commonly employed in the stone-finishing art. The means preferred, however, being of a positive nature, whereby there will 35 be no loss of motion between the said main driving-shaft and the table, and thus the table and the tool-carrier both receiving their power indirectly from the main driving-shaft by positive transmitting means, the said table 40 and carrier have a regular correspondence of movement, so that the work of tooling the stone will be uniform, and particularly when cross-tooling is effected the series of tool-indentures may be brought into alinement in 45 the manner described by me in the patent before referred to.

While I desire to operate the table by any of the well-known table-operating devices common in the art, I prefer for purposes of the 50 present case to employ, in connection with the said table and slideway, a screw-shaft *c⁴*, as shown more clearly in Figs. 1 and 12, where the said table *b* is shown to be provided on the under side with a threaded projection or nut *b'*, 55 Fig. 1, in which the said screw-shaft *c⁴* works, the rotation of the said screw-shaft causing the table to move back and forth on its slide-ways *a⁴* in the ordinary manner. Said screw-shaft *c⁴* is arranged in suitable bearings or 60 boxes *c⁵*, Fig. 12, formed on or secured to the bed-plate, and at the rear end is provided with a beveled gear-wheel *c³*, which intermeshes with a beveled gear-wheel *c²* on the main power-shaft *c'*. The said shaft *c'* is provided 65 with the ordinary means for securing a quick return movement of the stone-table and also a slow movement when the stone is under-

going the tooling operation. To secure the slow movement of the table during the tooling operation, I arrange on the driving-shaft *c'* a sleeve *c⁷*, having the beveled gear-wheel *c²* and pulley *c⁸*, the beveled gear-wheel being constantly in engagement with the larger beveled gear-wheel *c³* of the screw-shaft. To secure a fast return movement, I have also 70 arranged at the extremity of said shaft *c⁴* a beveled gear-wheel *c⁹*, which intermeshes with the bevel gear-wheel *c⁶* on the power-shaft *c'*, which last is driven by the pulley *c*. *c¹⁰* indicates an idle pulley on which the driving-belt may be shifted. While I prefer this arrangement of parts for transmitting power to the table, as before indicated, other means may be employed as circumstances may warrant.

The machine described in my former patent is capable of producing cross-tooling alone. When I mention "crandalling" in said patent, I mean the effect produced by a series of straight indentures or grooves in 90 alinement one with another, so as to produce a continuous groove extending across the stone or any ornament or face thereof.

In using the word "crandalling" in the present case I refer to a marking operation 95 producing an effect different in appearance from the effect produced by cross-tooling, the crandalling-marks being irregular and giving a granular appearance to the face of the stone.

By my present improvements the machine is made capable of not only producing the cross-tooling effect, but also the peculiar granular effect desired. To this end the tool-carrier *g* is not only given the movements referred to in my former patent—to wit, a horizontal sliding movement back and forth on the way *f*, whereby the tool is moved transversely to the direction of movement of the stone, and a vertical reciprocating movement 100 whereby the said tool is caused to rapidly engage the stone to produce the chiseling, cutting, or indenting effect—but is given a third rapid movement horizontally sidewise or at right angles to the direction of movement of the stone. The tool *v*, employed when such movement is given, consists of a collection or group of points, which points may be formed upon one or a series of tool-pieces properly fastened together and held 105 upon the carrier *g*. The quick lateral reciprocations of the vertically-reciprocating tool, taken in connection with the moving stone and the shape of the tool above referred to, produce the crandalling effect desired. To secure said quick lateral reciprocations of the tool, I have made the screw-shaft *f²* capable of longitudinal reciprocation 110 in its bearings, so that said shaft may not only be rotated to change the path of the tool over the stone, but may be given a limited longitudinal reciprocating movement in its bearings. To the end of said screw-shaft *f²* opposite that having the hand-wheel or crank 115

f^6 for turning said shaft I , couple said screw-shaft f^2 to a lever p , (shown in Fig. 9,) the said lever being properly provided with a threaded bushing loosely arranged therein, 5 so as to permit the desired movement of parts. Said lever p is fulcrumed at one end at p' upon a bracket q and at the opposite end is pivotally connected to the arm r' of an eccentric-strap r , in which an eccentric s operates to secure the rapid reciprocations of 10 parts.

To enable the indentations or chisel-marks to be of greater or less length horizontally, I have provided two eccentrics $s s'$, one adjustable in relation to the other, as indicated in 15 Figs. 1, 5, 9, and 10, one of which is keyed to the shaft, so as to move therewith and produce the reciprocating action, and the second of which is adjustable on the first and is bolted 20 thereto by bolts t , the inner eccentric being flanged and the flange t' being provided with a series of holes t^2 to receive said bolts and permit of adjustment in the strap. The eccentrics being fastened to the shaft, they rotate therewith and cause the eccentric-strap 25 and its arm r' to move backward and forward and oscillate the lever on its fulcrum p' . The movement of the lever p in turn causes the desired reciprocating longitudinal movement 30 to the screw-shaft f^2 and the tool-carrier and tool v , connected therewith.

To secure a greater or less indentation or depth of the cut or indentations on the stone, I have provided the double cam or eccentric 35 $e e'$ of the tool-carrier g , the outer of which is adjustable in relation to the inner cam or eccentric in the manner described in connection with the cams $s s'$ to effect the variation in the distance of stroke of the tools. In this 40 case the inner eccentric e' is keyed to the shaft d' , and the outer eccentric is adjustably fastened to the inner eccentric by bolts 12, Fig. 7.

To take up the lost motion due to wear, I 45 construct the link h as shown in Fig. 6, where the bearing for the eccentric is split, as at h' , the jaws $h^2 h^3$, which are perforated and the perforations threaded, being provided with screws h^3 to hold the jaws together and 50 with a limiting-screw h^4 , adapted to prevent the jaws being clamped with too great pressure upon the periphery of the eccentric. With this construction I can take up the lost motion due to wear with exactness and yet 55 prevent the link from so clutching the eccentric as to prevent an easy movement.

To prevent the tool from working when the stone is being rapidly moved to an initial position backward, and thus prevent an undue 60 rapid movement of the said tool, which would be very apt to injure the same or the gear-wheels transmitting power, I have arranged the bevel-wheel l ; by means of which power is transmitted from the gear-wheel k to the 65 shaft d' , fast upon a sleeve l' , having a head with a single ratchet-tooth l^2 . The said shaft d' is provided with a pawl-carrying collar u ,

which may be keyed to said shaft d' or otherwise affixed thereto, the said pawl-carrying collar u being provided with a pawl w and a 70 spring w' , by means of which the pawl is normally held into engagement with the ratchet-wheel. By having the single tooth upon the ratchet-wheel the tool will always be brought in cross-tooling to the proper position to secure the desired alinement. 75

While I have described the construction now preferred, I am aware that various modifications and changes of relation of parts may be made without departing from the scope 80 or spirit of my invention, and therefore I do not wish to be understood as limiting my invention when employing specific expressions in the description, excepting as the state of the art may require. 85

Having thus described the invention, what I claim as new is—

1. The improved cross-tooling and crandalling machine, comprising a frame having horizontal ways for a stone-carriage and vertical ways or bearings a', a' , a stone carriage or table and means for operating the same, a vertically-movable slideway and means for adjusting the same upon the ways a', a' , a head sliding horizontally upon said slideway and a screw-shaft for horizontally adjusting the same, a tool-carrier supported on said head and a tool, means for reciprocating said carrier vertically and means for reciprocating said screw-shaft longitudinally, substantially as set forth. 95

2. The improved cross-tooling and crandalling machine, comprising a frame having horizontal and vertical ways, a stone-carriage on said horizontal ways, means for operating the stone-carriage, a horizontal slideway adjustable on said vertical slideway of the frame and means for raising and lowering said horizontal slideway, a horizontal head f' , horizontally adjustable on said horizontal slideway and having vertical slideways, a tool-carrier arranged in the last said vertical slideways, and a tool, means for quickly reciprocating said tool-carrier vertically, a transverse horizontal screw-shaft supported at its ends upon the horizontal slideway and working in a correspondingly-threaded sleeve of the head f' , means for turning said shaft and means for reciprocating said shaft independent of its rotary movement, substantially as set forth. 110

3. The improved cross-tooling and crandalling machine, comprising a frame having horizontal and vertical ways, a stone-carriage on said horizontal ways and means for operating said carriage, a transverse slideway adjustable vertically on said vertical ways, a tool-carrier horizontally movable on said slideway, across the path of the stone-carriage and having an interiorly-threaded sleeve, a threaded shaft working in said sleeve and having its ends unthreaded and adapted to slide longitudinally, suitable bearings for said shaft at the ends of the slideway, and means for giv- 115 120 125 130

ing said shaft a reciprocating movement independent of its screw motion, substantially as set forth.

4. In a cross-tooling and crandalling machine, the combination with a vertically-adjustable horizontal slideway, of a tool-carrier supported on said slideway, and having a threaded sleeve, a correspondingly-threaded shaft working in said sleeve to adjust the tool-carrier laterally and having unthreaded portions lying in bearings in the frame of the slideway and being capable of a longitudinally-reciprocating movement in said bearings, a power-shaft, an eccentric on said shaft, and means for connecting said eccentric to the said threaded shaft and imparting reciprocating motion thereto, substantially as set forth.

5. In a cross-tooling and crandalling machine, the combination with a vertically-adjustable horizontal slideway, of a tool-carrier sliding on said slideway and having an interiorly-threaded sleeve, a correspondingly-threaded shaft working in said sleeve and turning in bearings at the ends of the slideway and being capable of longitudinal movement in said bearings, a power-shaft at right angles to said threaded shaft, an eccentric on said power-shaft, and a lever pivoted at one end and linked to said eccentric at the other, the end of the threaded shaft being secured to said lever at a point intermediate of its ends, substantially as set forth.

6. In a cross-tooling and crandalling machine, the combination with the tool, tool-carrier and transverse horizontal shaft for laterally adjusting said tool-carrier, said shaft being capable of both rotary and longitudinal movement, of means for longitudinally recip-

rocating said shaft, and comprising a sleeve 40 screwed on the end of said shaft, a lever *p*, pivoted at one end on a stationary support and perforated to receive said sleeve and allow the same to rotate without moving longitudinally, a power-shaft and an eccentric 45 thereon, said eccentric having an arm connected to the free end of said lever, substantially as set forth.

7. In a machine for cross-tooling stone, the combination with a tool-carrier, and a shaft 50 carrying an eccentric and connections for reciprocating the tool-carrier vertically, of a collar fast on said shaft, a pawl pivoted on said collar, a sleeve loose on said shaft and having a head with a single pawl-tooth adapted to be engaged by said pawl, and means for rotating said sleeve, substantially as set forth.

8. In a cross-tooling and crandalling machine, the combination of a vertical shaft *m*, carrying an eccentric and connections for 60 reciprocating the tool-carrier laterally and horizontally, a horizontal shaft carrying an eccentric and connections for reciprocating the tool-carrier vertically, a collar fast on said shaft, a pawl pivoted on said collar, a sleeve 65 loose on said shaft and having a head with a single pawl-tooth adapted to be engaged by said pawl, co-operating bevel-gears fast on said sleeve and the vertical shaft *m*, respectively, and means for driving said shaft *m*, substantially as set forth.

In testimony that I claim the foregoing I have hereunto set my hand this 2d day of June, 1899.

MONTGOMERY DENNIS.

Witnesses:

CHARLES H. PELL,
C. B. PITNEY.
